UNITED STATES PATENT OFFICE.

JAMES MILTON WAUGH, OF CHICAGO, ILLINOIS.

PLATFORM-BUFFER.

1,011,296.

Specification of Letters Patent. Patented Dec. 12, 1911.

Application filed September 28, 1908. Serial No. 455,106.

To all whom it may concern:

Be it known that I, JAMES MILTON WAUGH, a citizen of the United States, and a resident of the city of Chicago, county of Cook, and State of Illinois, have invented certain new and useful Improvements in Platform-Buffers; and I do hereby declare that the following is a full, clear, and exact description of the same, reference being had 10 to the accompanying drawings, and to the letters of reference marked thereon, which form a part of this specification.

In vestibule railway trains the end platforms of the cars are desirably brought in 15 such close relation with each other as to afford as nearly as possible a continuous floor or deck for the purpose of preventing accidental injury to passengers when passing from one car to another and also to exclude the upward and inward drafts of air 20 between the platforms that would otherwise be occasioned by the movements of the train. Of course, the rigid floor frame of the cars can never be brought into such 25 close relation as to well answer this purpose owing to the necessity for a resilient connection between the cars afforded by the draft gear and permitting relative movement 30 of adjacent cars with reference to each other. For this reason platform buffers have come into general use, the object being to afford a resilient extension beyond the ends of the car platforms and held outwardly by means of suitable spring gear, 35 which normally holds the buffer platform outwardly to a sufficient extent to insure a close engagement between the buffer platforms when the cars are coupled.

It is an object of the invention to afford 40 a platform buffer of the class described having under compression a limited rearward travel with relatively slight resistance after which greater stresses are absorbed by the draft gear.

45 It is a further object of the invention to afford in a device of the class described relatively flat, straight leaf springs in frictional bearing face to face throughout their entire extent and normally acting to hold the platform buffer extended but acting under compression to rapidly decrease the distance between bearing contacts of the spring, thus rapidly increasing the resistance to inward movement of the platform buffer.

55 It is a further object of the invention to afford in connection with the buffer springs

which normally act to hold the buffer extended, and the draft gear, a secondary spring or gear to assist in absorbing excessive stresses, so positioned as to be normally 60 out of action and capable of being brought into action only when the draft gear has acted to approximately half its maximum travel and by the use of which any desired capacity of absorption of buffering stress is 65 attainable without the necessity of sustaining these extreme stresses on the draft gear.

It is a further object of the invention to afford in a device of the class described a positive connection between the gear for the 70 platform buffer and the draft gear of the car whereby the more severe stresses in coupling or otherwise are transmitted directly to the draft gear and whereby in coupling the impact on the drawheads assists in reTRACTING the platform buffer to minimize to a degree the buffering shock thereon and deliver a part of the stress to a secondary buffering spring.

It is also important to afford a construction which affords great flexibility on curves without affecting the operation of the buffer platforms.

The invention embraces many novel features and consists in the matters hereinafter 85 described and more fully pointed out and defined in the appended claims.

In the drawings: Figure 1 is a fragmentary, horizontal section of a car platform provided with a device embodying my invention. Fig. 2 is a central longitudinal section thereof. Fig. 3 is a section taken on line 3—3 of Fig. 2. Fig. 4 is a section taken on line 4—4 of Fig. 2. Fig. 5 is a section taken on line 5—5 of Fig. 2. Fig. 6 is a fragmentary detail plan view showing 90 two cars coupled on curves.

As shown in the drawings: A, indicates the center sills of a car platform provided with devices embodying my invention. 100

A'—A², indicate transverse sills or blocks rigidly secured on the center sills at and near the end of the car platform, and which, as shown, afford abutments for the buffer embodying this invention, and on which, as 105 shown, rests the floor a—a' of the car.

Supported between the center sills A, in any suitable manner is a draft gear B, which, including the drawhead B', and its connections, may be of any standard type, 110 but, as shown, is of the class set forth in my patents for "draft rigging for railway cars,"

issued July 22, 1902, No. 705,172; "draft rigging for railway cars," issued June 23, 1903, No. 731,725; "draft rigging for railway cars," issued Jan. 7, 1902, No. 690,684; 5 "drawbar draft rigging for car couplers," issued Jan. 7, 1902, No. 690,683; "draft rigging for railway cars," issued April 17, 1906, No. 818,066; though, of course, draft gear of other types or kinds may be used, if 10 preferred.

Rigidly bolted to the sills is a transverse casing comprising a bottom wall or floor c , and side walls c' , of equal height and which extend nearly to the floor a , and are flanged 15 inwardly, as shown in Fig. 4, thus affording a casing open only at the top, the bottom, and the front end, and as shown, inwardly directed abutments or shoulders c^3 , are provided at the forward end of each of the side 20 walls c' . Within the casing thus formed and bearing against a plate c^4 , secured to the rear abutment or cross sill A' , is an abutment member c^5 , having a flat, rear face to bear against said plate and a convex face 25 extending transversely the car. Bearing against the same at the middle and fitting in said casing flat against each other is a group of spring plates indicated as a whole by C . Spaced therefrom by means of connected, 30 inwardly tapering spacing blocks c^6 , is a second group of spring plates C' , each bearing flat against the others. Bearing centrally against said second or outer group C' , of spring plates is an inwardly facing, 35 convex block c^7 , as shown in Fig. 1, the ends of which are engaged in the casing and behind the abutments c^3 . The length of said casing is such that the springs at all times 40 exert more or less pressure against the outer convex bearing blocks.

Said buffer block A^2 , is provided with apertures therethrough near each end and at the middle. Through the middle aperture extends the middle buffer stem, constructed, 45 as shown, of two bars D — D' , riveted together and the inner ends of which diverge as shown in Fig. 2, to engage between the same a transversely extended spring e^2 , and also the abutment head E . The latter, as shown, 50 is approximately equal in length to the distance between the center sills and the outer side thereof is convex and, as compared with the spacing blocks c^5 — c^7 , with a comparatively short radius. The rear side of said 55 abutment head is cut away at each end to permit the desired travel thereof and the central portion e , thereof is thus extended rearwardly and affords a flat face adapted to bear against the outer bearing block c^7 . Inserted through the yoke of said center stem 60 in advance of, and bearing against the convex face of the abutment head E , and pressed thereon by the laterally and rearwardly directed ends of a spring e^2 , is a group C^2 , of 65 relatively long, flat leaf spring plates. Slid-

able in the apertures in the ends of the buffer blocks A^2 , are lateral buffer stems E' , the inner ends of which are each provided with a head e^3 , carrying a stirrup or link e^4 , pivotally engaging the outer ends respectively 70 of the primary spring group C^2 , as shown in Fig. 1. Said buffer stems E' , extend beyond the outer end of the central buffer stem and at their extremities are coupled to, and support the buffer plate F , as shown in Figs. 75 1 and 2. Said buffer plate comprises an angle bar of suitable width of flange and web, which extends inwardly and is attached to the sliding floor section f' , which slides beneath the cover plate f^2 , as shown in Fig. 2, and as shown, on the outer side of said angle bar is a plate f^3 , which reinforces the same, all details of construction for buffer plates may, however, be as is usual with standard steel platforms for such cars. 80

Rigidly secured on the under side and inner end of the center buffer stem, and as shown, riveted through the abutment head E , is a buffering bar G , the rear or inner end of which extends downwardly and rearwardly 90 and is engaged on the draft yoke g , and tail straps g' , of the main draft gear by means of a bolt g^2 .

The operation is as follows: Inasmuch as the center buffer stem is rigidly attached by 95 means of the buffering bar G , to the main draft gear, the first stress in coupling is first applied on the main draft gear springs by engagement of the drawheads and acting to drive the drawheads inwardly to a greater 100 or less extent, the abutment head E , and yoke D , of course, moving inwardly under the stress, thus relieving the platform buffer of most of the stress of the blow it would otherwise receive. The buffer platforms 105 coming together however, the buffer stems E' , are first pressed inwardly by the buffering plates, thus flexing the spring group C^2 , around the abutment head E , and owing to the friction due to the surface resistance of 110 the plates in mutual engagement, absorbing a very large portion of any shock or impact thereon. If the inward stress be insufficient to force the buffer stems E' , inwardly to permit the buffer plate to engage the central buffer stem, of course, also of necessity forcing the draft head inwardly the stress for the first half of the inward travel of the drawhead is absorbed by the main draft gear springs. If the resistance in the main 115 draft gear be not sufficient to absorb the stress, the abutment block then engages the spacing plate or block c^7 , thus communicating the stress of the impact not only to the main draft gear but as well to the secondary 120 group or groups of springs C — C' , which thus, for the remainder of the inward travel under buffering serve a very important purpose as auxiliary buffering springs to absorb 125 excessive shock in buffering. Any desired ca- 130

pacity for absorbing the shocks may be secured to the construction, for it is only necessary to increase the number of plates in one or both groups or increase the number 5 of groups in the secondary or reserve casing, leaving the number of plates in each group the same, in either of which events the large frictional surface afforded by increasing the number of plates insures a greater resistance 10 because of such friction. The thickness of said plates in said groups, is far less important than the number of plates inasmuch as the absorption of stress either upon the main draft gear, the auxiliary gear, or the 15 platform buffer is due mainly to the frictional effect resulting from the large surfaces of said spring plates each in positive engagement with the corresponding surfaces of equal area of the adjacent plates, thus the 20 surface friction not only enormously augments the resistance of the springs to flexing under impact, but what is equally, if not more important, such friction actually absorbs the stress however applied and permits 25 the platform to return gently to normal whether the inward pressure, however excessive, be removed instantaneously or gradually. Nevertheless practically any stress in buffering may be absorbed first by the draft 30 gear during the first half of its travel and thence any desired additional resistance or absorbing power by varying the thickness and number of the reserve plates in the auxiliary set or sets. This auxiliary gear works 35 only under excessive buffering stress and under all other conditions is neutral and wholly out of action as is also the buffer platform spring group C², which is practically intended to maintain a light outward pressure 40 sufficient to hold the platforms in contact.

Of course, I am well aware that although I have shown my invention as embodied in connection with my own draft gear before mentioned, the construction may be employed with other draft gears, should it be desired, and furthermore, other details of the construction may be varied. I therefore do not purpose limiting this application for 45 patent otherwise than necessitated by the prior art.

I claim as my invention:

1. In a platform buffer, a center buffer stem, a rounded abutment block secured at the inner end thereof, a transversely extending 55 group of flat leaf springs bearing rearwardly on said abutment block, lateral buffer stems to the inner ends of which the group of springs are attached, and a spring at the rear of and adapted to be engaged by 60 said abutment block near maximum compressive stress.

2. A draft gear, a platform buffer operatively connected thereto and embracing a center buffer stem, a rounded abutment block 65 secured at the inner end thereof, a trans-

versely extending group of flat leaf springs adapted to bear rearwardly upon the rounded face of said abutment block, lateral buffer stems to the inner ends of which the group of springs is yieldingly attached 70 at its ends, a buffer plate secured on the ends of the lateral buffer stems and auxiliary buffer springs positioned to be engaged by said abutment head at about half the inward travel of the draft gear under abnormal 75 stress.

3. In a platform buffer the combination with the buffer plate, of lateral buffer stems on which the buffer plate is secured, a central buffer stem unconnected with the buffer 80 plate, and slotted at its inner end horizontally, a group of straight, flat, leaf springs extending through the slot in said buffer stem and connected with the inner ends of the lateral buffer stems, and bearing rearwardly at its middle on the center buffer stem, a draft gear, a rigid connection between the draft gear and the central buffer stem and auxiliary springs positioned behind said buffer stem and adapted to be engaged thereby when the draft gear and buffer platform have been forced inwardly about half their limit of travel in buffering. 85

4. In a platform buffer the combination with the draft gear and the buffer plates of a central and lateral buffer stems, the latter connected at their outer ends with the buffer plate, a rounded abutment block secured at the inner end of said central buffer stem, a group of duplicate straight, flat spring plates 90 bearing at their center rearwardly on the abutment block, means connecting the ends thereof swingingly with the lateral buffer stems, a rigid connection between the draft gear and said abutment block, and a reserve 95 shock absorbing device embracing groups of flat spring plates in frictional engagement throughout their entire face area, said groups so positioned as to be engaged and compressed by the abutment block when the draft gear and platform buffer have completed a part of their inward travel under compression. 100

5. In a device of the class described the combination with a draft gear and a platform buffer of a rigid connection between said draft gear and one of the buffer stems, a buffer spring acting to bear said buffer stem rearwardly under compression and an auxiliary shock absorbing device comprising a 110 casing and a plurality of groups of spring plates supported therein with the plates thereof in frictional engagement and positioned to be brought under compression when the draft gear has approximately 115 reached half its inward travel in buffering. 120

6. The combination with a draft gear and a buffer platform of a center buffer stem adapted to be forced inwardly under buffering stress, a group of transversely arranged leaf 130

springs in frictional bearing face to face and positively engaged at their ends with the buffer platform and at their middle engaging the central buffer stem, a casing at the 5 rear of said central buffer stem and groups of flat spring plates in frictional engagement in said casing and adapted to be engaged and compressed only as the draft gear and platform buffer approach the limit of travel 10 under compression, said plates acting frictionally to absorb both the impact and initial recoil.

7. In a device of the class described a platform buffer, a draft gear positioned below 15 the same and rigidly secured thereto, groups of spring plates arranged transversely at the rear of the platform buffer and adapted to be engaged and compressed by a part thereon only when the buffering stress is approaching the maximum absorbing power of the 20 draft gear.

8. In a device of the class described a casing, groups of leaf springs each comprising a plurality of flat, frictional engaging plates 25 of approximately equal length, and slideable in the casing, convex bearing blocks facing inwardly and centrally on the groups of springs in the casing, spacing blocks engaged between the ends of each group, said 30 casing and springs being disposed in alignment with, and at the rear of the central buffer stem and wholly disconnected from both the draft gear and platform buffer and adapted to come into action only to assist 35 in absorbing excessive stress in buffering.

9. A platform buffer in combination with the buffer stem, a transverse abutment head secured on the inner end thereof, leaf springs bearing rearwardly on the abutment head, a 40 spring acting to force the leaf springs at all times against the abutment block, lateral buffer stems extending beyond the central buffer stem and shackled to the ends of said group of springs, and a buffer platform supported 45 on the lateral buffer stems to flex the group of springs to carry the structure inwardly as a whole and a resilient stop for the abutment head.

10. A platform buffer embracing in connection with a center buffer stem yoked at 50 its inner end, a transverse abutment head secured in said yoke at the inner end, transverse leaf springs extending through the yoke and in flat frictional bearing face to face, a spring acting to force the same at all 55 times against the abutment block, lateral buffer stems extending beyond the yoke and shackled to the ends of said groups of springs and a buffer plate attached to, and 60 adapted first to engage the lateral buffer stems to flex the primary group of springs and next to impel the yoke and to carry the structure inwardly as a whole.

11. In a device of the class described a 65 buffer platform, a buffer spring consisting

of a group of friction spring plates, a bearing block having a curved face against which the spring bears, means pivotally connecting the ends of the spring and the buffer platform together, and means for yieldingly holding the buffer spring against the rounded face of the bearing block. 70

12. In a device of the class described a buffer platform, a spring consisting of friction spring plates, buffer stems pivotally connected to both the platform and spring, a central buffering stem non-connected to the buffer platform and connected with said spring and adapted to be engaged by the buffer platform in buffering, a bearing block 75 pivoted to the central buffering stem having a curved face against which the spring bears and an auxiliary buffering spring adapted to be actuated by engagement of the bearing block thereagainst. 80

13. In a device of the class described an initial buffering spring, a draft gear connected therewith and adapted to coact therewith in absorbing buffering stress, and an auxiliary buffering mechanism non-connected with either 90 the aforesaid buffering spring or the draft gear and adapted to absorb buffering stress only after the draft gear has been utilized to absorb part of the buffering stress. 85

14. In a device of the class described a buffer platform, a plurality of buffering mechanisms, means connecting one of the buffering mechanisms with the buffer platform, a draft gear and means connecting one of said buffering mechanisms with the draft gear necessitating the draft gear absorbing part of the buffering stress before one of the buffering mechanisms is brought into operation. 95

15. In a device of the class described a buffer platform, a buffer spring, buffer stems pivotally connected to the platform and spring, a member rounded adjacent the spring and an auxiliary buffering mechanism at the rear of said member adapted to be engaged by inward movement of said member. 100

16. In a device of the class a buffer platform, a buffer spring comprising spring plates in frictional engagement, means pivotally connecting the platform and ends of the buffer spring, a bearing member, a 115 spring for holding the buffer spring in engagement with the bearing member and an auxiliary buffering mechanism entirely unconnected with any part of the buffer platform and parts.

17. In a device of the class described a buffer platform, a spring comprising friction plates, a bearing member, buffer stems pivotally connected with the platform and the spring, a buffer stem pivotally connected 125 with the bearing member and an auxiliary buffering mechanism in alignment with the bearing member and adapted to be engaged thereby.

18. In a device of the class described a 130

buffer platform, a central buffer stem non-connected therewith, a bearing member secured thereto, a buffering mechanism adapted to be engaged by the bearing member, a draft gear and an initial buffering mechanism connected therewith and pivotally connected with the buffer platform.

19. In a device of the class described an initial buffering mechanism, a draft gear connected therewith and a secondary buffering mechanism positioned to be brought into operation by the aforesaid buffering mechanism when the buffering stress exceeds part of the capacity of the initial buffering mechanism and draft gear.

20. In a device of the class described a platform buffer, a spring pivotally connected therewith adapted to absorb initial buffering stress and then move inwardly without being further compressed, and a draft gear adapted to absorb buffering stress when the spring moves inwardly.

21. In a device of the class described, a buffer platform, an initial buffering spring comprising friction plates supported for either end to move relatively of the other in absorbing buffering stress, a link connected with the draft gear and adapted to be moved by the initial buffering spring after a predetermined buffering pressure has been exerted thereon, a draft gear and a secondary buffering mechanism positioned to coact with the main draft gear to absorb excessive buffering stresses.

22. In a device of the class described a buffer platform, a buffering spring comprising spring friction plates, means connecting the platform and buffering spring adapting either end of the buffering spring to yield relatively of the opposite end in buffering, means for preventing further absorption of stress by the buffering spring after a predetermined limit, and non-connected mechanisms adapted to

conjointly absorb all buffering stress after the buffering limit of the buffering spring is reached.

23. In a device of the class described a buffer platform, a movable pivot member, a spring comprising flat plates bearing at their middle on the pivot, connections between the buffer platform and ends of the spring for oscillating the spring on the pivot member, and a buffering mechanism adapted to be engaged by the movable pivot member and to coact with the spring in absorbing buffering stress.

24. In a device of the class described a buffer platform, a transversely extending buffering spring, a longitudinally movable bearing block acting as a pivot for the buffering spring to turn on, buffering stems connecting the ends of the buffering spring with the platform buffer and a link connected with the bearing block to be moved longitudinally by the buffering spring when the buffering stress exceeds its capacity.

25. In a device of the class described a buffer platform, a transversely extending buffering spring, a longitudinally movable bearing block acting as a pivot for the buffering spring to turn on, buffering stems connecting the ends of the buffering spring with the platform buffer, a longitudinally movable link connected with the bearing block to permit the buffering spring to move the same longitudinally when the buffering stress exceeds its capacity, and an auxiliary buffering mechanism engaged by the longitudinally moving bearing block to absorb buffering stress.

In testimony whereof I have hereunto subscribed my name in the presence of two subscribing witnesses.

JAMES MILTON WAUGH.
